UNITED STATES PATENT OFFICE.

JOHN H. BURKHOLDER, OF ASHLAND, OHIO.

DESIGN FOR A DOOR-HANGER PULLEY-FRAME.

SPECIFICATION forming part of Design No. 34,102, dated February 19, 1901.

Application filed January 18, 1901. Serial No. 43,812. Term of patent 7 years.

To all whom it may concern:

Be it known that I, JOHN H. BURKHOLDER, a citizen of the United States, residing at Ashland, in the county of Ashland and State of Ohio, have invented and produced a new and useful Design for Door-Hanger Pulley-Frames, of which the following is a specification.

My invention relates to a new and useful design for a door-hanger pulley-frame; and it consists of a metallic plate of the configuration and ornamentation shown in the accompanying drawings, in which—

Figure 1 is a front view; Fig. 2, a side view; Fig. 3, a rear view, and Fig. 4 a perspective view.

The leading feature of my invention consists of a substantially C-shaped metallic plate A, the ends thereof, B and C, being

slightly curved. The lower end C is set in and narrower than the upper end B, forming a hook D. Through the upper portion B there are provided circular apertures E and F through the front and back. These plates are sold to the trade and are used in conjunction with carrier-wheels adapted to be journaled in the apertures E and F of the hanger-frame.

What I claim is—

The design for a door-hanger pulley-frame, herein shown and described.

In testimony whereof I have hereunto set my hand in the presence of two subscribing witnesses.

JOHN H. BURKHOLDER.
